GOVERNOR FOR INTERNAL-COMBUSTION ENGINES

Marion Mallory, Detroit, Mich.

Application July 9, 1942, Serial No. 450,290

5 Claims. (Cl. 123—103)

This invention relates to a governor for an internal combustion engine and more particularly to a governor which controls the charge in the intake passageway of an internal combustion engine so as to govern the speed of the engine.

Engine speed governors at present in use are complicated in structure and not altogether dependable in operation. It is the object of the invention to produce a governor for an internal combustion engine which is simple in structure and very dependable in operation.

The drawing shows a sectional view of a carburetor and engine intake manifold with a suction controlled governor valve.

The governor about to be described can be used satisfactorily with any type of internal combustion engine regardless of how the fuel and air are mixed preparatory to burning in the engine. For example, the governor can be used just as well on an engine of the injection type wherein the raw fuel is injected into a cylinder as well as on an engine of the carburetted type where the fuel and air are passed through and are mixed in a carburetor. Therefore, by way of description rather than for purposes of limitation, the invention is exemplified by showing the same in combination with a carburetor 1 having a butterfly throttle valve 2 mounted on shaft 4. 3 is a throttle arm fixed on shaft 4 exteriorly of carburetor housing 1. 5 designates an auxiliary throttle housing located between the carburetor 1 and the engine (not shown). The engine intake manifold is designated 16. An auxiliary throttle valve 8 is mounted on shaft 7 journaled in housing 5. A crank arm 9 is fixed on shaft 7 exteriorly of housing 5. 9 is a rod pivotally connected at one end with arm 8. The other end of rod 9 is fixed to piston 11 which is reciprocably mounted in cylinder 10. A compression spring 12 tends to hold piston 11 toward the outer end of cylinder 10. Cylinder 10 is connected by conduit 14 with a vacuum pump 13. The vacuum pump 13 can be of any conventional type such as a rotary vane type vacuum pump, a centrifugal vacuum pump, or a rotary blade type pump. Pump 13 is provided with a shaft 15 which is driven by the internal combustion engine.

Cylinder 10 and piston 11 are merely exemplary of a suction device which can be used with the vacuum pump to control the governor. A flexible diaphragm type of suction device is just as suitable as the cylinder and piston type of suction device. The important thing is that the pump 13 should be operated directly or indirectly

through the engine and in accordance with the speed of the engine so that the vacuum created by the pump would vary directly with the speed of the engine, that is, the greater the speed of the engine the greater the vacuum that the pump will pull or create in cylinder 10.

The governor valve 6 is slightly unbalanced, that is, the area of that part of valve 6 above its axis of rotation is greater than the area of that part of valve 6 below its axis of rotation, as shown in the drawing. Unbalancing of valve 6 makes possible the use of a smaller vacuum pump because the velocity of the charge flowing by the unbalanced valve 6 assists the vacuum pump in closing the valve.

The line 14 between the vacuum pump 13 and cylinder 10 is provided with an air bleed in the form of cylinder 18 which communicates with conduit 14 through opening 21. Cylinder 18 is provided with air vents 20 and 22 and houses a piston valve 23 which is normally held open by compression spring 19.

The operation of the device is as follows: Assuming throttle valve 2 is held wide open, the engine will receive a full charge. As the speed of the engine increases the speed of shaft 15 will correspondingly increase. The pump 13 will be air bled through orifices 22, 21 and line 14 but as the speed of shaft 15 increases the vacuum created by vacuum pump 13 will increase in proportion to the increase of engine speed and as the engine speed increases the vacuum will increase in cylinder 18 until the vacuum in cylinder 18 reaches a point where the atmospheric pressure acting on piston 23 collapses spring 19 and causes valve 23 to close orifice 21. Immediately upon the closing of orifice 21 the vacuum quickly increases in the cylinder 10 thereby causing the atmospheric pressure to act on piston 11, overcoming the spring 12 and thereby assisting the valve 6 to move towards closed position. As valve 6 moves toward closed position, the charge admitted to the engine is reduced and prevents the engine from overspeeding. Since valve 6 is unbalanced, the velocity of the charge flowing through the intake passageway by valve 6 assists the vacuum pump and suction device 10, 11 in closing the valve.

One of the disadvantages or weaknesses of the velocity governor, such as the unbalanced valve 6, is the so-called surging or hunting, that is, the unbalanced governor valve normally tends to vibrate thereby causing variations in the speed of the engine. My unbalanced governor valve 6 is

stabilized by the vacuum pump 13 and suction device 10, 11 so that it will not surge or vibrate.

Whenever the speed of the engine falls below a predetermined speed the vacuum will fall in conduit 14 and cylinder 18 thereby permitting spring 19 to withdraw valve 23 and open port 21 which causes a sudden falling of the vacuum in cylinder 18 which permits spring 12 to quickly open governor valve 6.

I claim:

1. A governor for an internal combustion engine having an intake passageway comprising an unbalanced throttle valve positioned in said intake passageway for controlling the charge to said engine so that the charge flowing by the unbalanced throttle valve urges the same towards closed position, and supplementary means controlled in accordance with the speed of the engine for assisting the unbalanced governor valve to close when the engine reaches a predetermined speed and for opening the unbalanced throttle valve when the engine falls below a predetermined speed, said supplementary means serving to stabilize the unbalanced valve and prevent vibrating of the same.

2. A governor for an internal combustion engine having an intake passageway comprising an unbalanced throttle valve positioned in said intake passageway for controlling the charge to said engine so that the charge flowing by the unbalanced throttle valve urges the same towards closed position, a suction device connected to said unbalanced valve, said suction device serving to stabilize the unbalanced valve and prevent vibrating of the same, and a vacuum pump independent of said engine and operated in accordance with the speed of the engine, a conduit connecting said vacuum pump to said suction device whereby when the engine reaches a predetermined speed the vacuum produced by said pump acts through said suction device and moves the throttle valve towards closed position, and resilient means for moving the throttle valve towards open position when the speed of the engine falls below a predetermined speed and the vacuum drops in the said suction device.

3. A governor for an internal combustion engine comprising a throttle valve, a suction device, a connection between the suction device and the

said throttle valve, a vacuum producing pump connected to said suction device and adapted to be driven so that as engine speed increases the vacuum created by said pump will increase, an air bleed to atmosphere for said pump, a valve controlling said air bleed and responsive to a predetermined vacuum created by said pump whereby said valve closes said air bleed at a predetermined desired speed and the full vacuum of the pump is impressed on the suction device which moves said throttle valve toward closed position to decrease the charge entering the engine.

4. A governor for an internal combustion engine comprising a throttle valve, a pressure responsive device, a connection between the pressure responsive device and the said throttle valve, fluid pressure producing means connected to said pressure responsive device and adapted to be actuated so that the effective pressure produced by said means will vary in accordance with the speed of the engine, an air bleed to atmosphere for said means and a valve controlling said air bleed and responsive to a predetermined pressure created by said means whereby said valve closes said air bleed at a predetermined engine speed and the full pressure created by said means is impressed on the pressure responsive device which moves said throttle toward closed position to decrease the charge entering the engine.

5. A governor for controlling an internal combustion engine comprising in combination a rotary source of power, an engine controlling valve, a pressure responsive device, a connection between the pressure responsive device and the said control valve, a vacuum producing pump operated by said power and adapted to be driven so that as the engine speed increases the vacuum created by said pump will correspondingly increase, a conduit connecting said vacuum producing pump to said pressure responsive device, an air bleed to atmosphere for said pump, a valve controlling said air bleed and responsive to a predetermined vacuum created by said pump whereby said valve closes said air bleed and the full vacuum produced by the pump is impressed on the pressure responsive device which moves said control valve toward closed position to control the speed of the engine.

MARION MALLORY.
